UNITED STATES PATENT OFFICE.

JAMES W. VANMETER, OF SAN FRANCISCO, CALIFORNIA.

STAMP-MILL.

1,353,096.

Specification of Letters Patent. Patented Sept. 14, 1920.

Application filed June 30, 1919. Serial No. 307,680.

To all whom it may concern:

Be it known that I, JAMES W. VANMETER, a citizen of the United States, residing at the city and county of San Francisco and 5 State of California, have invented certain new and useful Improvements in Stamp-Mills, of which the following is a specification.

My invention relates to the class of 10 stamp-mills.

My mill though comprising a mortar and a stamp, differs essentially from the ordinary stamp-mill, in that instead of the stamp reciprocating and playing into and 15 out of a fixed mortar, the mortar reciprocates over a fixed stamp, and by this movement crushes its ore against the stamp.

This reversal of the ordinary operation results in several distinct advantages which 20 it is the object of my invention to attain.

One of these advantages is that the heavier and finer particles, due to the jar of impact of the moving mass, gravitates to the bottom quicker while the lighter and 25 larger particles seek the top and thus come in direct contact with the stamp. Consequently, a new surface of the ore is constantly presented to the stamp. This effect eliminates sliming to great extent, the ore 30 mass changing relative position of particles at each upward stroke and jar of the mortar. This cannot be the case with a dropping stamp which will strike the ore on a practically unchanging top, the bottom of 35 the mass remaining intact. By my reversed arrangement I thus increase the crushing capacity. Moreover by this constant, repeated and rapid changing of the ore due to the moving and jarring mass, I get a 40 better battery amalgamating effect within the mortar, by bringing the fine gold in quicker contact with the mercury.

Still another advantage lies in keeping the screens clear. In common practice the 45 mortar screens are often choked by fine particles of ore. It is well known that if the pulp is not discharged at once when reduced to the desired fineness, it rapidly slimes, which is detrimental to the treatment. My device prevents clogging of the screens, because any particles of ore that 50 may tend to clog are thrown off by the rapid and forcible impact of the mortar against the stamp.

With these ends in view my invention 55 primarily consists in a stamp-mill compris-

ing a fixed frame, a reciprocative mortar mounted in the frame; and a fixed stamp carried by the frame, and over which the mortar plays to crush its ore by impact 60 against the stamp. Moreover, in order to make my mill practical in construction and operation, my invention consists, further, in combining with the mortar and stamp, an engine, preferably of the internal combustion type, the reciprocative member of 65 which is connected with the mortar, and in operating this engine automatically by the contact of its control connections carried by the cylinder with the fixed frame. By 70 this form of motive power and device my stamp-mill is made more valuable by increasing its capacity, yielding better amalgamating results, cheapness in construction and less weight; also more economical in 75 horse power and readily set up without skilled labor. It also dispenses with heavy cams, long drops, and cumbersome castings, making a mill which can be transported to and worked at high altitudes and in cold 80 climates without danger of breaking.

Referring to the accompanying drawings—

Figure 1 is an elevation of my stamp-mill.

Fig. 2 is a vertical section of the same 85 partly in elevation.

Fig. 3 is a vertical sectional detail at right angles to Figs. 1 and 2, showing the water circulation.

Fig. 4 is a vertical section, enlarged, of 90 the upper portion of the mill, showing the contacts for the internal combustion engine.

Fig. 5 is a detail section showing the compressed air ducts and controlling valves. 95

Fig. 6 is a detail section showing the fuel ducts and controlling valves.

Fig. 7 is a detail of the switch for the ignition plug.

1 is an upright frame with a base 2 and 100 a head 3, said frame being adapted to be anchored to a suitable foundation. 5 is a mortar having a die 4 and fitted with screens 6. The mortar is carried by columns 7 to which it is securely fixed and 105 clamped between the bottom nuts 8 and the shoulders 9 on the columns. The columns 7 slide through the head 3 of the frame 1, in suitable bushings 10, whereby the mortar is adapted for reciprocative movement. 110

To the upper ends of the columns 7 is securely clamped between top nuts 11 and

shoulders 12, the cylinder 13 of an internal combustion engine, said cylinder being adapted for reciprocative movement, whereby through the columns 7, the mortar is given its movement. The cylinder 13 moves upon a stationary piston 14, the lower end of which rests firmly and solidly upon the head 3 of the frame 1, as seen in Figs. 2 and 3.

10 15 is a stationary stamp within the mortar 5 and over which said mortar moves. The stem 15' of the stamp is fitted in the head 3 of the frame 1, being secured therein by set screws 16, Figs. 1 and 3, and is held 15 rigid and fixed against upward impact by its bottom shoulder 17 below said head.

18 is a cushion member in the base 2 of the frame 1, to serve as a buffer for the mortar to rest upon when inactive. It will 20 now be seen that if the cylinder 13 be given a reciprocative movement, it will lift and lower the mortar, with the effect of subjecting the ore in the mortar to impact with the stationary stamp, which is the operation 25 sought.

The means for reciprocating the cylinder 13 will now be described.

In the head of the cylinder is the usual ignition plug 19, and below the head and 30 above the piston is the combustion chamber 20 of the cylinder, to receive the explosive charge, Figs. 2, 3 and 4.

The piston 14, below its upper end, is formed with a packed enlargement 14', and 35 between this enlargement and a shoulder 21 in the cylinder bore is formed an air compression chamber 22. In this chamber air is compressed by utilizing the weight of the cylinder and mortar on their downward 40 stroke, and this air acts as a cushion in the operation of the mill, and the air thus compressed is directed, to avoid waste, into the air reservoir from which the air is obtained for the explosive mixture, as will be presently described.

By referring to Fig. 3 it will be seen that both the combustion chamber 20 and the air compression chamber 22 are water-jacketed as shown at 23, and the piston itself is also 50 provided for water circulation, being made hollow and provided with a central longitudinal partition 24, as seen in Fig. 3.

The water enters the hollow piston by the flexible connection 25, and thence circulates 55 over the top of the partition 24, and leaves by the flexible connection 26, which communicates with the water jacket space 23. The water thence passes to the top of the cylinder and issues therefrom by a pipe 27 which 60 leads down to a point where it discharges directly into the mortar, as seen in Fig. 3. The water thus used has the double function of cooling the parts by and through 65 which it circulates, and being thus heated is used as hot water in the mortar, to aid

the process of amalgamation therein, and to reduce the danger of the castings breaking when worn. This is a decided advantage where mills are used in a cold climate.

The valve mechanism is as follows:— 70

In the upper end of the cylinder is fitted a tubular valve sleeve or seat 28, Fig. 4, in which reciprocates a piston valve 29 which controls the air inlet port 30 to the combustion chamber 20, and also controls the 75 upper series of ports 31 in said valve seat which communicate with the inlet port 30, and the lower ports 32 which admit the air to said valve seat from the air connection leading from the compressed air reservoir, as will be presently described. When the piston valve 29 is lowered it opens the ports 30 and 31 to exhaust the burnt gases through the open top of the valve sleeve or seat, and when it is raised it connects the 80 ports 31 and 32, to admit compressed air to the combustion chamber.

The travel of the valve 29 is limited downwardly by the lower seat-shoulder 33 and is limited upwardly by the upper seat-shoulder 34. A stem 35 extends downwardly from the valve 29, and said stem is fitted with an upper spring 36 and a lower spring 37, the former spring tending to lift the valve and the latter spring to lower it. 90 The stroke of the valve 29 is effected as follows.

In Fig. 4, 38 is a swinging catch pivoted in the cylinder at 39, said catch operating alternately above and below a lug 40 on the 100 valve stem 35, to prevent the valve from rising when the catch engagement is above the lug and to prevent it from descending when the engagement is below the lug. A spring 41 acting on the catch 38 holds it 105 against the valve stem.

42 is a vertically movable rod, the lower end of which projects below the cylinder body and said rod is supported by a collar 43 and is held down by a spring 44, resting on a collar 45 of the rod and adapted at its upper end to come in contact under the catch 38, when the rod moves upwardly, due to the contact of the lower projecting end of said rod with the head 3 of the 115 frame 1.

It will now be seen that when the cylinder 13 moves down, so that the end of rod 42 contacts with the fixed frame head 3, said rod will move up and through the spring 120 44 will release the catch 38 from above the lug 40 of the valve stem 35. Since, due to the same downward movement of the cylinder, the spring 36 of said valve stem is compressed, said spring will now, when the catch 38 is released, throw the stem up, thus causing the piston valve 29 to rise and bring the ports 31 and 32 into communication with the combustion chamber 20 through port 30 so as to charge the latter 130

with compressed air, the catch 38 returning under the lug 40 and holding the valve up.

On the upstroke of the cylinder, the catch 38 having by the impact of the ore against 5 the stamp been jarred loose from under the lug 40, the spring 37 pulls the valve 29 down, permitting exhaust from the combustion chamber.

In Fig. 5 is shown the valve controlled 10 connection to the air compression cushion chamber 22, and from said chamber to the air reservoir which latter is not shown herein, it being any suitable source of compressed air.

15 48 is a spring controlled inwardly opening air inlet valve which communicates at one side with the exterior air, and at the other side with a port 49 into the chamber 22, (Fig. 4).

20 50 is a spring controlled outlet valve from said chamber port 49, the compressed air passing up through a duct 51 leading to the connection 51' from the air reservoir, Figs. 1 and 5, said connection 51' having a 25 spring controlled check valve 52 which permits the air from the reservoir to pass freely into the combustion chamber, but allows no burnt gases or back pressure into the air duct 51. The compressed air stored 30 up in the reservoir may be used to run the engine temporarily in emergencies.

In Figs. 4 and 6 are shown the fuel pump. 35 53 is a bore in the cylinder 13, the upper portion of the bore having a communication 54, Figs. 6 and 1, with the compressed air connection 51' from the air reservoir. In this bore is fitted a piston 55 which has a stem 56 extending downwardly through an adjustable bushing 57, the projecting lower 40 end of said stem being adapted to contact with the head 3 of the frame 1 on the downward stroke of the cylinder. 58 is the inlet valve of the fuel connection and 59 is the outlet valve communicating with the fuel 45 pipe 60 leading to and through the top of the cylinder and opening into the combustion chamber 20—Figs. 4 and 1. When the stem 56 strikes the fixed frame head 3, the piston 55 is forced up and thereby opens the 50 inlet valve 58 and closes the outlet valve 59, thus sucking in the fuel to the lower side of the piston in the bore 53. When the cylinder 13 rises, the compressed air from the connection 54 forces the piston 55 down and 55 thus forces fuel out through valve 59 and pipe 60 into the combustion chamber.

The ignition of the charge is effected by the contact of the switch terminal 46 with the collar 47 conveniently carried on the 60 water pipe 27—(see Fig. 7).

The complete operation may now be described. In Figs. 2 and 4 the mortar 5 and cylinder 13 are on the downward stroke, and the exhaust gases are escaping from the

combustion chamber 20 by way of the ports 65 30 and 31, and the open upper end of the valve sleeve or seat 28. The spring 36 of the valve stem 35 is being compressed and the lower spring 37 is expanding. The spring 36 is tending to force the valve 29 up, 70 but said valve is held by the catch 38 bearing on top of lug 40. But the moment the end of the rod 42 contacts with the fixed head 3 of the frame 1, the upward movement of the spring 44 disengages the catch 75 38 from above the lug 40, and thereupon the spring 36, throws up the valve 29, bringing the ports 31 and 32 into communication both with the compressed air reservoir and with the combustion chamber 20, and thus air is 80 admitted to the latter. Fuel having been sucked into the pump by the rise of piston 55, due to contact of the stem 56 with the head 3, the mortar and cylinder now start on their upward stroke, and the stem 56 being 85 relieved, its piston is forced down by the compressed air through connection 54, and their charge of fuel is delivered through pipe 60 to the combustion chamber. Then the explosive charge in the combustion 90 chamber is ignited and the cylinder is driven up with great pressure, causing the ore in the mortar to strike the stamp. The impact and sudden jar causes the swinging catch 38 to disengage from below the lug 95 40, and the spring 37 then pulls the valve 29 down closing the air supply and allowing the exhaust gases to pass out.

I claim:—

1. A stamp-mill comprising a fixed frame; 100 a mortar mounted on the frame for reciprocative movement; a stamp fixedly mounted in the frame and over which the reciprocative mortar plays to crush the ore by impact against said stamp; a cylinder connected with the mortar; a piston fitted in said cylinder fixed against reciprocative movement; fluid controlling connections to reciprocate said cylinder on said fixed piston; and means carried by the cylinder and actuated by contact with the fixed frame for operating said fluid controlling connections. 105

2. A stamp-mill comprising a fixed frame; 110 a mortar mounted on the frame for reciprocative movement; a stamp fixedly mounted in the frame and over which the reciprocative mortar plays to crush the ore by impact against said stamp; an engine, the reciprocative member of which is connected with and reciprocates the mortar; means for 115 circulating cooling water about the heated parts of said engine; and means for introducing said water heated during its circulation, into the mortar in heated condition. 120

3. A stamp-mill comprising a fixed frame 125 having a head; columns mounted slidably in said head for reciprocative movement; a mortar fixed to one end of said columns; a

reciprocative cylinder of an engine fixed to the other end of said columns; a stamp fixed in the head of the frame and over which the mortar plays to crush the ore by impact against said stamp; a stationary piston supported on the head of the frame, and over which the engine cylinder plays; means for reciprocating the cylinder; and means carried by the cylinder and operating by contact with the frame head to actuate said reciprocating means.

4. A stamp-mill comprising a fixed frame; a mortar mounted on the frame for reciprocative movement; a stamp fixedly mounted in the frame and over which the reciprocative mortar plays to crush the ore by impact against said stamp; and an engine the cylinder of which is reciprocative and is connected with and reciprocates the mortar and the piston of which is stationary, said piston having an enlargement associated

with a chamber in the cylinder to form an air cushion for the reciprocative mortar.

5. A stamp-mill comprising a fixed frame having a head; columns mounted slidably in said head for reciprocative movement; a mortar fixed to one end of said columns; a cylinder fixed to the other end of said columns; a stamp fixed in the head of the frame and over which the mortar plays to crush the ore by impact against said stamp; a stationary piston supported on the head of the frame and over which the cylinder plays; and means for reciprocating said cylinder.

In testimony whereof I have signed my name to this specification in the presence of two subscribing witnesses.

JAMES W. VANMETER.
